UNITED STATES PATENT OFFICE.

LOUIS FRIEDMAN, OF NEW YORK, N. Y.

DESIGN FOR A BOW TIE.

Application filed May 28, 1927. Serial No. 22,220. Term of patent 7 years.

To all whom it may concern:

Be it known that I, LOUIS FRIEDMAN, a citizen of the United States, residing at New York, in the county of New York and State of New York, have invented a new, original, and ornamental Design for a Bow Tie, reference being had to the accompanying drawing, forming part thereof.

Fig. 1 is a perspective view of a bow tie showing my new design.

Fig. 2 is a top plan view of the same.

I claim:

The ornamental design for a bow tie, as shown.

In testimony whereof I have affixed my signature.

LOUIS FRIEDMAN.
